UNITED STATES PATENT OFFICE.

WILLIAM H. CONAWAY, OF WICHITA, KANSAS.

APPARATUS FOR HANDLING FENCE-WIRE.

1,327,024.

Specification of Letters Patent.

Patented Jan. 6, 1920.

Application filed March 31, 1919. Serial No. 286,385.

To all whom it may concern:

Be it known that I, WILLIAM H. CONAWAY, a citizen of the United States, residing at Wichita, in the county of Sedgwick 5 and State of Kansas, have invented new and useful Improvements in Apparatus for Handling Fence-Wire, of which the following is a specification.

My present invention has to do with apparatus for handling fence wire; and it has for one of its objects to provide an apparatus of the character stated, adapted to be readily converted from a fence wire handling apparatus into a hand truck and vice 15 versa.

Another object of the invention is the provision of an apparatus for handling fence wire embodying such a construction and relative arrangement of parts that it is 20 adapted to be used to advantage in unwinding or letting off wire, in stretching wire and in reeling or winding the wire upon a reel.

Other objects and practical advantages of 25 the invention will be fully understood from the following description and claims, when the same are read in connection with the drawings, accompanying and forming part of this specification, in which:

30 Figure 1 is a general view illustrating the manner in which my apparatus is used to unwind or let off wire.

Fig. 2 is a general view showing the use 35 of the apparatus as a wire stretcher.

Fig. 3 is a similar view showing the apparatus positioned for use as a wire winder or reeling apparatus.

Fig. 4 is a view showing the apparatus as 40 it appears when converted into a hand truck.

Fig. 5 is an enlarged view showing the removable transverse spindle of the apparatus and the parts carried thereon.

Fig. 6 is a detail view illustrating the 45 brake complementary to the said spindle.

Fig. 7 is an enlarged transverse section, taken in the plane indicated by the line 7-7 of Fig. 4 and showing the bearings for the transverse spindle.

Fig. 8 is a view of the reel, removed from 50 the spindle.

Fig. 9 is a detail section on line 9-9 of Fig. 7.

Similar numerals of reference designate 55 corresponding parts in all of the views of the drawings.

The main frame of my novel apparatus is

made up of side bars 1, which terminate at their rear ends in handles 2, cross-bars 3, permanently fixed between and connecting the side bars, and anchors 4, which form the forward terminals of the side bars, and are disposed at about the angle illustrated to said side bars, and are connected together by a cross-bar 5. The said anchors are pointed, and are provided with heels 6, as illustrated, whereby foot pressure may be conveniently applied to the spikes to drive the same into the ground when the apparatus is positioned as shown in Figs. 2 and 3. When the apparatus is converted into a truck the 70 said spikes, together with their cross-bar 5, form the usual guard at the forward end of the truck frame. At 8 the frame is equipped with ground wheels for use when the apparatus is employed as a truck and also for 75 use when it is employed to let off wire as shown in Fig. 1. It will also be noticed that the rear cross-bar 3 of the frame terminates in legs 9, disposed at right angles to the major portion of the bar and adapted to 80 serve as truck legs or rests.

Pivotedly mounted on the rear cross-bar of the frame are brace bars 10. These brace bars 10 respectively comprise an inner tubular section 11, having a collar 12 at its 85 free end, an outer pointed member 13 telescopically arranged in the tubular member, and a set screw 14 bearing in the collar 12 and adapted to adjustably fix the member 13 with respect to the member 11. Manifestly, 90 by reason of their pivotal mounting on the rear cross-bar 3 of the frame, the brace bars 10 are adapted to be employed as shown in Fig. 2, or as shown in Fig. 3, and are also adapted upon the apparatus as shown in Fig. 95 1, or when the apparatus is converted into a truck, to lay idly on the cross-bars of the frame where they will be entirely out of the way.

On the lefthand side bar of the frame is 100 an enlargement 15, fixed to said side bar and having a bearing seat 16. A shackle 17 is hinged at one end to said enlargement 15 and has its free portion removably disposed in a slot 18 in the enlargement 15, and also 105 has its free portion threaded for the engagement of a nut 19. On the opposite side bar 1 of the frame is a cruciformed bearing member 20, loosely mounted on the side bar and retained in position by cotter pins 21 or other 110 suitable means. The transverse portion of the bearing member 20 is adapted to receive

one end portion of a spindle 22, the other end portion of which is disposed in the seat of the bearing member 15 and under the shackle complementary thereto. By virtue 5 of this provision, when the shackle is unfastened and swung upwardly the end of the spindle adjacent to the bearing member 15 may be readily swung upwardly for the placing of a reel 23 on the spindle or 10 the removal of the reel from the spindle. The spindle 22 is provided at 24 with a left-hand threaded portion of comparatively large diameter, and at the outer end of the portion 24, is an abutment 25, which merges 15 into a brake disk 26. At the outer side of the disk 26 a spindle is provided with a journal portion 27, and at the outer end of said journal portion, which is adapted to turn in the bearing member 20, the spindle is provided 20 with a portion 28, of angular form and cross section, and a threaded terminal 29. At 30 is a removable clamping disk detachably secured by a cotter 31 on the spindle 22, a complementary clamping disk 32 is loose on the spindle and disposed 25 against the inner end of the threaded portion 24. A lefthand threaded nut 35 having a handle 36 is mounted upon the threaded portion 24 of the spindle and is adapted to 30 crowd the disk 32 inwardly with a view to clamping and holding the reel 23 between the disks 30 and 32. By virtue of the left-hand threads on the spindle portion 24 and in the nut 35, any tendency of the reel to 35 turn on the spindle 22 when the apparatus is used in the manner shown in Fig. 2 will have the effect of tightening the clamping of the wheel between the disks 30 and 32.

In order that the user of my novel apparatus may retard the rotation of the reel 23 when the apparatus is used after the manner shown in Fig. 1, I provide the brake mechanism shown. The said brake mechanism comprises a lug 40 carried by the frame adjacent 40 to the righthand handle 2, a pivoted hand lever 41 adapted to engage the lug 40 and be adjustably fixed thereby, and a rod 42 terminating at its forward end in a brake band 43, that surrounds and is opposed to 45 the perimeter of the disk on the spindle. Manifestly, by manipulating the lever 41 the operator is enabled to exert great pressure on and adequately brake the disk and the spindle 22, and by placing the lever 41 in engagement with the lug 40 the operator 50 is enabled to retain the spindle 22 in a braked state.

Removably secured on the angular end of the spindle 22 is a crank 50 to which is fixed 55 a ratchet 51. A pawl 52 is pivoted to one side bar on the main frame in position to engage said ratchet with a view to precluding retrograde rotation of the crank, the spindle and the reel, and so as to retain the wire that is being stretched under tension.

In order to properly guide the wire that is being stretched, I provide a sheave 60, carried in a bent holder 61, which is shaped to fit around the outer member of one telescopic brace, after the manner shown in Fig. 2. 70 The said sheave rests adjacent to the fence post, and is designed to permit of the wire being stretched at any point on the post.

The operation of my improvement in its several uses will be thoroughly understood 75 from the foregoing description. I would say, however, that when the apparatus is used to let off wire, as shown in Fig. 1, it is simply necessary for the operator to grasp one of the handles and draw the apparatus 80 after him over the ground. When the apparatus is used as shown in Fig. 2, the operator, by manipulating the crank, is enabled to exert a strong and steady pull upon the wire without liability of the wire being 85 permitted to slip in the direction away from the apparatus. When the apparatus is used as shown in Fig. 3, turning of the spindle and the reel will be attended by taking up of the wire on the reel in a neat and compact 90 manner. When it is desired to convert the apparatus into a truck, it is simply necessary to remove the reel and the spindle, together with the appurtenances of the latter from the main frame, and from this it follows that 95 the apparatus may be as readily converted from a truck into a fence wire handling apparatus by replacing the spindle, the reel and the spindle appurtenances in the frame.

In any one of the uses to which the apparatus is put incidental to the handling of fence wire, the brake mechanism hereinbefore explicitly described is calculated to enable the operator to check or retard the reel 100 at any time desired. It will also be manifest that by releasing the lever 41 from engagement with the lug 42, the reel may be rendered free at any time desired during the operation.

The specific construction herein illustrated 110 and described constitutes the best practical embodiment of my invention of which I am cognizant. I do not desire, however, to be understood as confining myself to the said specific construction, inasmuch as in the future practice of the invention changes in the form and arrangement of the parts may be made without involving departure from the scope of my invention as the same is defined by my appended claims.

Having described my invention, what I claim and desire to secure by Letters Patent, is:

1. In a convertible hand truck and fence-wire handling apparatus, the combination of 125 a frame, having side bars with combined anchors and guards at the forward ends thereof and handles at the rear ends; the said combined anchors and guards having heels at their inner ends disposed at an angle to the 130

side bars, wheels carried at the forward portion of the frame, and means on the side bars of the frame for the connection thereto of a reel and reel appurtenances.

- 5 2. In means for the purpose described, a frame having side bars connected together and terminating at their rear ends in handles and at their forward ends in combined anchors and guards; the said anchors and 10 guards being tapered toward their free ends, and being provided with heels disposed at an angle to the side bars, and wheels carried at the forward portion of the frame.
3. In means for the purpose described, the 15 combination of a frame having connected side bars terminating at their rear ends in handles, and at their forward ends in combined anchors and guards; the said anchors and guards having heels at their rear ends 20 disposed at an angle to the frame, wheels carried at the forward portion of the frame, a cross-bar interposed between the rear portions of the side bars of the frame, and braces comprising tubular members pivoted 25 on said cross-bar, outer members telescopically arranged in the tubular members, and adjustable means for adjustably fixing the

outer members with respect to the inner members.

4. In means for the purpose described, the 30 combination of a frame having side bars, a cruciformed bearing member loosely mounted upon one of the side bars and having a transverse journal bearing, means for retaining said bearing member against end- 35 wise movement on the side bar, a bearing member carried by the other side bar and having a detachable spindle-retaining shackle, and a spindle journaled in said bearing members and equipped with a detach- 40 ably connected disk, and a loose opposed disk; said spindle being provided with a lefthand threaded portion at the outer side of the loose disk, a nut equipped with a handle and provided with a lefthand thread and 45 mounted on said threaded portion of the spindle, a crank removably arranged on the spindle and provided with a ratchet, and a pawl pivoted on the adjacent frame bar and engaging said ratchet. 50

In testimony whereof I have affixed my signature.

WILLIAM H. CONAWAY.
